DESIGN FOR A WIND VANE FOR BICYCLES OR THE LIKE

William G. Fletcher, Bogota, N. J.

Application April 30, 1942, Serial No. 106,762

Term of patent 3½ years

To all whom it may concern:

Be it known that I, William G. Fletcher, a citizen of the United States, residing at Bogota, in the county of Bergen and State of New Jersey, have invented a new, original, and ornamental Design for a Wind Vane for Bicycles or the like, of which the following is a specification, reference being had to the accompanying drawing, forming part thereof.

Fig. 1 is a front elevation of a wind vane for bicycles, or the like showing my new design, and Fig. 2 is a side elevational view thereof.

I claim:

The ornamental design for a wind vane for bicycles or the like, as shown.

WILLIAM G. FLETCHER.
